UNITED STATES PATENT OFFICE.

ALBERT HOSSFELD, OF LEWISTON, MINNESOTA.

TONGS FOR PICKING UP POTATOES AND THE LIKE.

1,316,157.

Specification of Letters Patent. Patented Sept. 16, 1919.

Application filed March 29, 1919. Serial No. 286,037.

To all whom it may concern:

Be it known that I, ALBERT HOSSFELD, a citizen of the United States, residing at Lewiston, in the county of Winona and 5 State of Minnesota, have invented certain new and useful Improvements in Tongs for Picking Up Potatoes and the like; and I do hereby declare the following to be a full, clear, and exact description of the invention, 10 such as will enable others skilled in the art to which it appertains to make and use the same.

My invention relates to improvements in tongs, especially adapted for use in picking 15 up potatoes and the like; and, to this end, generally stated, it consists of the novel devices and combinations of devices herein-after described and defined in the claims.

In the accompanying drawings, which 20 illustrate the invention, like characters indicate like parts throughout the several views.

Referring to the drawings,

Figure 1 is a perspective view showing an operator holding in one hand a pair of the 25 improved tongs and in his other hand a basket which he slides or drags over the field to receive the potatoes picked up by said tongs;

Fig. 2 is a perspective view of the improved tong;

Fig. 3 is an end elevation of the same with one of the legs shown in a closed position by means of dotted lines; and

Fig. 4 is an end elevation of the improved 35 tongs holding a potato.

The legs 5 and 6 of the improved tongs are connected, at one of their ends, by a flat U-shaped spring that is rigidly secured thereto by rivets or otherwise. The ends 40 of the spring 7 are preferably set into the legs 5 and 6, so that their outer faces are flush therewith, as well as the rivets which connect the same to said legs. The free or other end of each leg is bifurcated to afford 45 a pair of tongs 8.

A flexible strap 9, of rubber or of other suitable material, connects the prongs of each pair at their inner faces. Interposed between the prongs 8 of each pair, is a coiled 50 spring 10 which yieldingly holds said prongs spread and the respective strap 9 taut. To limit the opening and closing movements of the legs 5 and 6, there is rigidly secured between the prongs 8 of the leg 5, at the crotch 55 of said prongs, a flat link 11, which projects between the prongs 8 of the leg 6. A cotter

pin 12, passed through any one of a plurality of longitudinally spaced holes 13 in the link 11, outward of the leg 6, limits the opening or spreading movement of the legs 5 and 6, 60 and a cotter pin 14, passed through any one of said holes between said legs, limits the closing movement of said legs. Obviously, these cotter pins 12 and 14 afford adjustable stops on the link 11 to limit the opening and 65 closing movements of the legs 5 and 6.

The leg 5, at its inner or spring-connected end, is expanded to afford a hand hold 15 by which an operator *b* may hold the prongs and operate the leg 6 with his thumb to close 70 said leg. Potatoes *c*, picked up by the improved tongs, as shown in Fig. 1, are preferably placed in a metal basket or other receptacle *d* having a bail *e*, which the operator holds in his other hand, and pushes or 75 drags the basket with him, as he walks over the field and picks up the potatoes with the improved tongs. The potatoes are held between the flexible straps 9, as best shown in Fig. 4, and which straps do not mar or bruise 80 the potatoes. With a little practice, an operator can pick up potatoes very quickly with the improved tongs, without having to stoop over, which, of course, makes the work of picking up potatoes very easy and less 85 tiresome. When the basket is filled, the potatoes may be emptied into a sack or a wagon box. By adjusting the inner pin or stop 14, the size of potatoes held by the tongs may be varied, at will. The link 11 guides the legs 90 5 and 6, during their opening and closing movements, and holds the same against lateral movement with respect to each other.

What I claim is:—

1. A pair of tongs having their legs 95 spring-connected at one end and bifurcated at the other to afford pairs of prongs, and flexible straps connecting the prongs of each pair, said pairs of prongs being under strain to hold the flexible straps taut.

2. A pair of tongs having their legs spring-connected at one end and bifurcated at the other to afford pairs of prongs, flexible straps connecting the prongs of each pair, and springs under strain to separate the 105 prongs of each pair.

3. A pair of tongs having their legs spring-connected at one end and bifurcated at the other to afford pairs of prongs, flexible straps connecting the prongs of each pair, and a link pivoted between and to the prongs of one of said legs and working between the 110

- prongs of the other said legs as a guide to limiting the opening movement of said legs.
4. A pair of tongs having their legs spring-connected at one end and bifurcated at the other to afford pairs of prongs, flexible straps connecting the prongs of each pair, a link rigidly secured to one of said legs and extending between the prongs of the other thereof, and an adjustable stop on the link for limiting the closing movement of the legs.
5. A pair of tongs having their legs spring-connected at one end and bifurcated at the other to afford pairs of prongs, flexible straps connecting the prongs of each pair, a link rigidly secured to one of said legs and

extending between the prongs of the other thereof, and adjustable stops on the link for limiting the opening and closing movements of said legs.

20

6. A pair of tongs having their legs spring-connected at one end and bifurcated at the other to afford pairs of prongs, and flexible straps connecting the prongs of each pair, one of said legs at its spring-connected end being expanded to afford a hand piece.

25

In testimony whereof I affix my signature in presence of two witnesses.

ALBERT HOSSFELD.
